TWO-STAGE CONVERSION PROCESS FOR THE PRODUCTION OF AROMATIC PRODUCT FRACTIONS

Harold F. Mason, Berkeley, Calif., assignor to California Research Corporation, San Francisco, Calif., a corporation of Delaware

Filed May 13, 1959, Ser. No. 812,883

9 Claims. (Cl. 208—59)

This invention relates to a process for the catalytic conversion of hydrocarbon feed stocks and, more particularly, relates to an improved process for converting such feed stocks to product fractions boiling below the feed stocks employed.

A process has recently been developed for the conversion of aromatic hydrocarbon-containing distillates having an initial boiling point of about 350° F. to high octane gasoline fractions boiling below said feed stocks. The process comprises passing such a feed stock, along with hydrogen, to a conversion zone for contact with a catalyst comprising a hydrogenating component dispersed on an active cracking support at a pressure of at least 400 p.s.i.g. and at temperatures of from about 350° F. to about 800° F. Although the process has utility with a wide variety of feed stocks, it has been found to be particularly useful in the processing of hydrocarbon feed stocks having a relatively high aromatic hydrocarbon content to produce high octane gasoline fractions boiling below about 300° F. When operating in this manner, the procedure involves separating the conversion zone effluent into one or more normally gaseous fractions, a product gasoline fraction boiling below about 300° F. and a bottoms fraction boiling above said gasoline fraction which is normally recycled to the conversion zone as a component of the feed.

It has now been found that the above noted process, directed to the production of high octane gasoline fractions boiling below about 300° F., can be materially improved by the process of the present invention, it resulting in the production of a gasoline fraction having a higher octane number than heretofore considered possible.

According to the present process, an aromatic hydrocarbon-containing feed stock having an initial boiling point of about 350° F. and at least 2,000 s.c.f. of hydrogen per barrel of said feed stock, are contacted in a first conversion zone with a catalyst comprising a hydrogenating component dispersed on an active acid cracking catalyst support, said catalyst having a severity factor (as that term is hereinafter defined) in the range of about 0.1 to 2.0. The contacting step is conducted at pressures of at least 400 p.s.i.g. and at temperatures in the range of from about 350° to about 800° F. The operating conditions maintained in the first conversion zone are such that the per-pass conversion of the feed stock to hydrocarbons boiling below about 350° F. is in the range of from about 40 to 80 volume percent. The effluent from the first conversion zone is separated to recover at least one normally gaseous fraction, at least one aromatic hydrocarbon-containing gasoline fraction boiling below about 300° F., an intermediate fraction boiling in the range of from about 300 to 350° F., and a bottoms fraction boiling above said intermediate fraction. Said bottoms may be recycled, at least in part, to the first conversion zone. At least a portion of the intermediate fraction and at least 2,000 s.c.f. of hydrogen per barrel of the intermediate fraction are contacted in a second conversion zone with a catalyst of the same general type as employed in the first conversion zone under such conditions of pressure and temperature within the defined operating ranges of the first conversion zone that the per-pass conversion of the intermediate fraction to hydrocarbons boiling below

2

about 300° F. in the second conversion zone is in the range of from about 10 to 50 volume percent. The effluent from the second conversion zone is then separated to recover at least one normally gaseous fraction, at least one aromatic hydrocarbon-containing gasoline fraction boiling below about 300° F., and a bottoms fraction. The 300°-350° F. portion of the bottoms fraction may be recycled to the second reaction zone and the 350° F.+ portion of the bottoms may be returned to the first reaction zone.

The feed stock employed as fresh feed to the first conversion zone in accordance with the subject invention may be any conventional hydrocarbon distillate fraction having a basic nitrogen content of less than 25 p.p.m. and having an initial boiling point of about 350° F., preferably boiling in the range of from about 350° to 650° F., and which also preferably contains at least 50 percent by volume of aromatic hydrocarbons. Such feed stocks may be of petroleum origin or they may be obtained from shale, gilsonite, coal tar or other natural sources. In this connection, the word "aromatic" is employed in the conventional sense to include all those hydrocarbons incorporating an aromatic nucleus which may be either unsubstituted or substituted with one or more various aliphatic or other groups. While referred to as hydrocarbons, they may also contain other atoms such as nitrogen, oxygen, sulfur and the various metals commonly found in petroleum and other distillates of natural origin. A preferred feed stock to the first conversion zone normally meeting the criteria of boiling range, aromatic content, and nitrogen level comprises the higher boiling components of the effluent of a catalytic reforming unit. Such effluents (commonly termed reformates) are conventionally produced by passing straight run, thermally cracked or catalytically cracked naphthas, along with hydrogen, through a reforming unit provided with a platinum-on-alumina or molybdenum-alumina catalyst under well-known reforming conditions. Other preferred feed stocks include concentrates rich in aromatic hydrocarbons or as may be obtained by the extraction of various hydrocarbon fractions with sulfur dioxide, furfural, or the like.

One of the important variables in the conduct of the subject process which has a material effect and to that extent, permits the production of the desired gasoline products, is the control of the nitrogen content of the feed stock. As indicated, an acceptable nitrogen level expressed as basic nitrogen is about 25 p.p.m., although appreciable further improvement is obtained as the nitrogen content is reduced to levels below 10 p.p.m. When the feed stock is not already sufficiently low in nitrogen, these levels may be reached by conventional denitrification procedures, such as by hydrofining the feed stock, which involves treating the same with hydrogen at elevated temperatures and pressures in the presence of a hydrogenating catalyst which has little cracking activity and little tendency to saturate aromatics under the conditions employed. The effluent from such pretreating steps, if satisfying the specification boiling ranges and aromatic content, may be fed directly to the first conversion zone or it may be subjected to a preliminary separation or fractionation to recover a specification feed.

The catalyst employed in both conversion zones of the subject process is a multifunctional catalyst composition comprising a hydrogenating component dispersed on an active acidic cracking support wherein the catalytic components are critically balanced to result in a catalyst severity factor of from about 0.1 to 2.0. The cracking component or support may comprise any one or more of such acidic materials as silica-alumina, silica-magnesia, silica-alumina-zirconia composites, as well as certain acid-treated clays and similar materials. A preferred cracking support for the catalyst composition employed in the present invention

tion is comprised of a synthetically prepared composite of silica and alumina.

The hydrogenating component of the catalyst may be selected from any one or more of the various group VI and group VIII metals, as well as the oxides and sulfides thereof, representative materials being the oxides and sulfides of molybdenum, tungsten, chromium, and the like, and/or such metals as nickel or cobalt and the various oxides and sulfides thereof. Also suitable are certain group I (B) or group II (B) metals, such as copper or cadmium and their oxides and sulfides. If desired, more than one hydrogenating component may be present, e.g., composites of two or more of the oxides and/or sulfides of molybdenum, cobalt, nickel, copper, chromium and zinc.

Depending on the activity thereof, the amount of the hydrogenating-dehydrogenating component may be varied within relatively wide limits of from about 0.1 to 35%, based on the weight of the entire catalyst composition. Within these limits, the amount of said component present should be sufficient to provide a reasonable catalyst on-stream period at required conversion levels, but insufficient under the reaction conditions employed to effect substantial saturation of any except highly substituted aromatic ring compounds and of any small amounts of polynuclear aromatic compounds which may be present.

The balance of catalytic components necessary to effect the desired selectivity in the multiphase reactions of the process is determined by reference to the "severity factor" (S_a) of the catalyst composition. This characteristic of the catalyst may be determined by subjecting the catalyst to a standardized test wherein the reference feed stock is a trimethylbenzene, such as pseudocumene, or an equilibrium mixture of trimethylbenzenes which may be obtained from a catalytically reformed naphtha. When employing the latter trimethylbenzene concentrate, a narrow boiling fraction having a D-86 distillation range from about 318° to 335° F. and a C₉ aromatic content of at least 95 volume percent should be used. The test involves passing the reference feed stock through the test catalyst at a liquid hourly space velocity of 2.0 with 9,000 s.c.f. of hydrogen per barrel of feed while maintaining a catalyst temperature of 650° F. and a pressure of 1,200 p.s.i.g. This test operation is continued for a period of time (usually about 2 to 5 hours) sufficient to stabilize the system, and thereafter for a time sufficient to provide an adequate product sample. After flashing to atmospheric pressure the liquid product is then fractionated to determine the volume percent of product boiling below 300° F., relative to feed. This is taken as the synthetic product. Aromatic contents of the reference feed and said synthetic product are determined, as by chromatographic analysis (FIAM method), and the severity factor, S_a , is calculated from the expression:

$$S_a = \frac{A_f}{A_p} - 1$$

where A_f = volume percent aromatics in the feed, and A_p = volume percent aromatics in said synthetic product.

For operations in the subject isocracking process, i.e., the reactions in both conversion zones, the severity factor (S_a) must have a value falling within the range of from about 0.1 to 2.0. An S_a value greater than 2.0 reflects an undesirable loss in aromatic content in the product, as well as a high hydrogen consumption. On the other hand, S_a values below 0.1 normally reflect actual formation of aromatics and such reactions are undesirable for the purposes of this invention since they involve rapid catalyst deactivation due to deposition of coke, etc. Catalysts having S_a values higher than the desired range can usually be brought into compliance by suitably adjusting the amount of the hydrogenating component present, reducing the hydrogen partial pressure, or other measures to reduce hydrogenation activity.

Particularly good results from the standpoint of good selectivity and the ability to withstand repeated regenera-

tion with relatively minor decreases in activity are obtained with catalysts composed of from 1 to 30% nickel sulfide or cobalt sulfide deposited on the aforementioned synthetically prepared silica-alumina composites.

The following description, taken in conjunction with the accompanying figure illustrates a preferred simplified flow scheme of the conversion process of the present invention.

Fresh feed, as hereinbefore defined, enters the system either as a liquid, vapor or mixed liquid-vapor phase by line 10 in which the feed is admixed with a recycle stream 11 (described below) and hydrogen entering line 10 by lines 12, 13 and 14. The amount of hydrogen entering line 10 by line 12 is at least 2,000 standard cubic feet per barrel of total feed (including both fresh feed, as well as recycle stream 11). Normally, from about 1,000 to 2,000 s.c.f. of hydrogen are consumed in the conversion reaction per barrel of total feed converted to synthetic product, i.e., that boiling below the initial boiling point of the particular feed. In the present process, hydrogen stream 12 is derived from a hydrogen recycle stream 13 and a make-up hydrogen source entering the system by line 14.

The total feed and hydrogen pass from line 12 into the first conversion zone 15 which is operated at elevated pressures and temperatures. The pressure employed in conversion zone 15 is in excess of about 400 p.s.i.g. and may range upwardly to as high as 5,000 p.s.i.g., with a preferred pressure range being from about 600 to 2,500 p.s.i.g.

Conversion zone 15 is maintained at reaction temperatures ranging from about 350° to about 800° F. In preferred practice, the temperature at which the conversion is initiated in a given on-stream period should be as low as possible (within the noted range and commensurate with the maintenance of the desired per-pass conversion levels in each zone, as discussed below) since the lower the starting temperature the longer will be the duration of the on-stream period. In addition, liquid yields will be higher, and gas yields lower at the lower temperatures.

In conversion zone 15 the per-pass conversion to products boiling below the initial point of the total feed is kept within the range of from about 40 to 80 volume percent. This per-pass conversion level can be maintained by correlations of, in particular, space velocities of the feed through the conversion zone and/or temperature. Preferably, a relatively constant conversion within the defined per-pass conversion level is observed. This can be accomplished by periodically increasing the catalyst temperature (within the aforementioned range) to compensate for any catalyst fouling. The natural decline in conversion level, after fairly long on-stream periods, can also be offset to some extent by lowering the space velocity of the feed, although this procedure is generally not as satisfactory as accomplishing the same result by temperature adjustment. Still other methods of maintaining the desired conversion level will suggest themselves to those skilled in the art such as by maintaining the reaction at a constant temperature and allowing the per-pass conversion to decline within the specified ranges.

The total effluent from the first conversion zone 15 is passed by line 16 into high pressure separator 17 wherein a hydrogen-rich overhead is fractionated off and returned as the hereinbefore noted recycle by line 13. Of course, this hydrogen recycle stream may be purified, if desired, by any suitable means. The hydrogen-lean remainder of the zone 15 effluent, preferably reduced to essentially atmospheric pressure and augmented by a recycle stream 18 (discussed below), is passed by line 19 into fractional distillation column (or separation zone) 20 in which separation of the feed effluent into various fractions is accomplished. In this particular process design, a normally gaseous product, containing, for example, C₄ hydrocarbons and lighter, is removed overhead by line 21 and passed to storage. (Obviously, the com-

position of this overhead fraction can be regulated to remove, for example, C_3 's and lighter or C_5 's and lighter.) The desired gasoline product cut boiling below about 300° F. is removed from column 20 by line 22 from which it is passed into reflux drum 23. A portion of this gasoline product is passed as reflux by line 24 from drum 23 and the remainder is passed to storage by line 25.

At least two additional fractions are separated in column 19; one, an intermediate fraction boiling from about 300° to 350° F., and the other the bottoms fraction. The latter is passed by line 11 to line 10 to form part of the initial feed as hereinbefore described. The intermediate fraction is passed by line 26, along with recycle and make-up hydrogen entering line 26 by lines 27 and 28, respectively, into the second conversion zone 29. The amount of hydrogen entering conversion zone 29 by lines 27 and 28 will be within the same range as that described with respect to the hydrogen employed in the first conversion zone 15, namely, at least 2,000 s.c.f. per barrel of feed. The hydrogen in line 27 comprises a recycle stream (described below) and that in line 28 is derived from a source outside of the present process scheme.

The catalyst and the conditions employed in the second conversion zone 29 fall within the hereinbefore defined catalyst compositions and conditions employed in the first conversion zone 15. The operating conditions and catalyst composition within zone 29 are adjusted such that the per-pass conversion of the feed to products boiling below 300° F. is from about 10 to 50 volume percent. The desired per-pass conversion level can be maintained in the same manner as that described above with respect to the first conversion zone 15. The total effluent from second conversion zone 29 is passed by line 30 into high pressure separator 31 wherein a hydrogen-rich recycle stream is flashed off and passed by line 27 into line 26. The remainder of the second conversion zone effluent is preferably reduced to about atmospheric pressure and passed by line 18 to line 19 from which it enters fractional distillation column 20 and is separated in accordance with the description above.

As noted hereinbefore, the above described flow scheme is a preferred method of conducting the subject process. However, it is obvious that many modifications can be made in the system without departing from the scope of the invention. Thus, instead of employing the common fractional distillation column 20, a number of columns or separators could be used to perform essentially the same function. In such a system, low pressure gas-liquid separators could be employed in line 19 and/or line 18 to separately remove, for example, a C_1 to C_4 normally gaseous fraction, or each effluent from conversion zones 15 and 29 could be separately fractionated. In the latter case, advantage could be taken of the fact that the portion of the effluent from the second conversion zone 29 boiling above about 350° F. is particularly rich in C_{10} aromatics, such as durene, and these could be separated from the effluent for chemical and other uses.

A further modification of the process involves adapting the separation section to recover xylenes. It has been found that the subject multistage conversion process is an excellent producer of xylenes which can be recovered, for example, by a further distillation of the C_5 to 300° F. product recovered from the described process by line 25. Of course, the other various separation techniques to recover these xylene products from the conversion zone effluents are apparent to one skilled in the art.

A still further modification of the process could employ once through operation in either or both reaction zones 15 and 29. Once through operation in zone 29 would require separate distillation of products from zones 15 and 29.

The reactions in each of the conversion zones in the present invention can be conducted by employing fixed or moving catalyst beds, fluid catalysts or slurry catalyst systems with fixed bed operations preferred. It is often possible to extend on-stream times in the conversion zones

over such long periods that it becomes uneconomical to provide catalyst regeneration facilities. However, catalyst regeneration can be done, either in situ or in separate regeneration zones by conventional regeneration techniques.

Extensive experimental data covering variations in feed composition, catalyst and operating variables have been utilized in the development of a plant process design incorporating the inventive features of the subject two-stage process as well as single-stage operations wherein all products from the single conversion zone boiling above about 300° F. are recycled thereto. In the following table, case 1 summarizes the results that can be expected when the process described above is operated according to conditions falling within the scope of the invention, namely, a 60 percent per-pass conversion level in the first conversion zone and a 35 percent per-pass conversion in the second conversion zone. For comparative purposes only cases 2, 3 and 4 show the results that can be expected when employing a single conversion zone at per-pass conversions below 300° F. of 33, 41.5 and 60 percent, respectively. In all cases, results were predicated upon the use of the same catalyst, namely, 2.5 weight percent (of the entire catalyst) nickel as the sulfide on an active silica-alumina cracking catalyst support and upon the same fresh feed, namely, a 350° to 475° F. reformate containing 93+ percent aromatic hydrocarbons having a nitrogen content less than 25 p.p.m.

Table I

	Case No.			
	1	2	3	4
35				
First Conversion Zone:				
Temp., °F.	730	730	730	730
Pressure, p.s.i.g.	1,200	1,200	1,200	1,200
Hydrogen, s.c.f./bbl. feed	6,400	6,400	6,400	6,400
Per-pass conversion below 300° F., Percent		33	41.5	60
Per-pass conversion below 350° F., Percent	60			
Recycle, °F.	350+	300+	300+	300+
Second Conversion Zone:				
Feed, boiling range, °F.	300-350			
Temperature, °F.	730			
Pressure, p.s.i.g.	1,200			
Hydrogen, s.c.f./bbl. feed	6,500

50 From the table it can be seen that the two-stage process of the present invention (case 1) is capable of producing a higher octane C₈ to 300° F. gasoline fraction than any of the single-stage operations with comparable yields of this gasoline fraction.

55 The references to boiling points or ranges as employed in the specification and claims are those measured in accordance with either of the ASTM distillation procedures D-86 or D-158, depending upon the reference boiling range. It is furthermore to be understood that, 60 in respect to the designations of boiling ranges and feed and product distillation cut points, a 10 percent by volume tolerance is to be permitted in order to more closely approximate the practical limitations of industrial distillation equipment and practices.

65 I claim:

1. In a process for producing aromatic hydrocarbon-containing product fractions boiling below about 300° F. wherein an aromatic hydrocarbon-containing feed, containing less than 25 p.p.m. basic nitrogen, at least 50 percent by volume of aromatic hydrocarbons and having an initial boiling point of about 350° F., and at least 2000 s.c.f. of hydrogen per barrel of said feed are contacted in a conversion zone with a catalyst comprising a hydrogenerating component dispersed on an active acid cracking catalyst support, said catalyst having a severity factor in

the range of about 0.1 to 2.0, and wherein the contacting step is conducted at pressures of at least 400 p.s.i.g. and at temperatures in the range of from about 350° to 800° F., the improved method of operation which comprises adjusting the reaction conditions in said conversion zone such that the per-pass conversion of said feed to hydrocarbons boiling below about 350° F. is in the range of from about 40 to 80 volume percent, separating the effluent from said conversion zone to recover at least an aromatic hydrocarbon-containing product fraction boiling below about 300° F., an intermediate fraction boiling in the range of from about 300° to 350° F. and a bottoms fraction boiling above said intermediate fraction, contacting at least a portion of said intermediate fraction and at least 2000 s.c.f. of hydrogen per barrel of said intermediate fraction in a second conversion zone with a catalyst of the same type as employed in the first conversion zone under such conditions of pressure and temperature within the defined operating ranges of the first conversion zone that the per-pass conversion of said intermediate fraction to hydrocarbons boiling below about 300° F. in said second conversion zone is in the range of from about 10 to 50 volume percent, and separating the effluent from said second conversion zone to recover the aromatic hydrocarbon-containing product fraction boiling below about 300° F. produced in said second conversion zone.

2. The process of claim 1 wherein at least a portion of the bottoms fraction separated from the effluent of the first conversion zone is recycled to that zone.

3. The process of claim 1 wherein the effluent from the second conversion zone is separated to produce said product fraction and a second intermediate fraction boiling from about 300° to 350° F. and returning said second intermediate fraction to said second conversion zone.

4. The process of claim 1 wherein the effluent from the second conversion zone is separated to produce said product fraction and a residual fraction and passing said residual fraction into said first conversion zone.

5. The process of claim 1 wherein the effluents from both conversion zones are separated in a common fractional distillation zone.

6. The process of claim 1 wherein a xylene-containing fraction is recovered from at least one of the product fractions boiling below about 300° F.

7. A process for producing maximum yields of highly aromatic hydrocarbon-containing gasoline boiling below

10

about 300° F. which comprises maintaining two conversion zones in each of which hereinafter defined hydrocarbon fractions are contacted with hydrogen in the presence of a catalyst comprising a hydrogenating component disposed on an active acid cracking catalyst support and having a severity factor in the range of about 0.1 to 2.0, said conversion zones each being operated at pressures of at least about 400 p.s.i.g. and at temperatures in the range of from about 350° to 800° F., contacting a feed hydrocarbon fraction having an initial boiling point of about 350° F. composed predominantly of aromatic hydrocarbons and having a basic nitrogen content of less than 25 p.p.m. and at least 2000 s.c.f. of hydrogen per barrel of feed with said catalyst in the first of said conversion zones under such conditions that the per-pass conversion of said feed to hydrocarbons boiling below about 350° F. is in the range of from about 40 to 80 volume percent, separating the effluent from the first conversion zone to recover at least a highly aromatic hydrocarbon-containing gasoline boiling below about 300° F., an intermediate fraction boiling from about 300° to 350° F. and a bottoms fraction boiling above about 350° F., contacting said intermediate fraction and at least 2000 s.c.f. of hydrogen per barrel of said intermediate fraction with said catalyst in the second of said conversion zones under such conditions that the per-pass conversion of said intermediate fraction to hydrocarbons boiling below about 300° F. is in the range of from about 10 to 50 volume percent, and separating the effluent from the second conversion zone to recover additional quantities of a highly aromatic hydrocarbon-containing gasoline boiling below about 300° F.

8. The process of claim 7 wherein at least a portion of said bottoms fraction is passed into said first conversion zone.

9. The process of claim 7 wherein the effluents from said conversion zones are separated in a common fractional distillation section.
